[57] ABSTRACT

A tether-ball assembly where an elongated bar is supported at a given elevation above a supporting surface. An elongated flexible tether element is connected to the bar intermediate the ends thereof and has a ball attached thereto distant from the bar. Thus a player on one side of the bar can propel the ball to the other side thereof. The bar together with the structure for supporting it on the supporting surface and the component for attaching the tether to the bar are all capable of being assembled and disassembled without the use of any tools and occupy a small space when disassembled, so that the structure is easy to set up for use and disassembled for storage.

TETHER-BALL SUPPORT ASSEMBLY

BACKGROUND OF THE INVENTION

The invention relates to games.

In particular, the present invention relates to tether-ball games.

There are many known games involving the use of a tethered ball, but all of these games suffer from various drawbacks. For example, many of these games require special components which must be fixed rigidly to suitable supports such as walls, floors or the like, in order to be able to use the tether-ball assembly. Other types of tether-ball games limit the number of players which can participate and limit the type of action which can be carried out.

It is primarily for these reasons that tether-ball assemblies are not more popular, although they do form a potential source of enjoyable exercise.

SUMMARY OF THE INVENTION

It is accordingly a primary object of the present invention to provide a tether-ball assembly which will avoid the above drawbacks.

In particular, it is an object of the present invention to provide a tether-ball assembly which can be assembled and disassembled without the use of any tools and which does not require any fixed attachment to any robust supporting surface such as a floor or a wall.

Furthermore, it is an object of the invention to provide a tether-ball assembly which can be enjoyably used either by a single player or by as many as four players, for example.

Furthermore, it is an object of the invention to provide a tether-ball assembly which can be dismantled and stored in an extremely small space while at the same time being capable of being readily set up in a short time in any desired location when it is desired to use the tether-ball assembly.

According to the invention, the tether-ball assembly includes an elongated bar means and a support means which supports the bar means at a given elevation above a supporting surface. An attaching means is carried by the bar means intermediate its ends, and an elongated flexible tether means is connected at one end to the attaching means to be attached thereby to the bar means. A ball is connected to the end of the flexible tether means distant from the bar means, so that a player on one side of the bar means can propel the ball to the other side thereof.

BRIEF DESCRIPTION OF DRAWINGS

The invention is illustrated by way of example in the accompanying drawings which form part of this application and in which:

FIG. 1 is a perspective illustration of the tether-ball assembly of the invention in its assembled condition where it is set up ready for use;

FIG. 2 is an exploded perspective illustration of the various components of the assembly of the invention;

FIG. 3 is a fragmentary partly sectional longitudinal elevation of the part of the tether-ball assembly to which the tether is attached;

FIG. 4 is a transverse, fragmentary sectional elevation taken along line 4-4 of FIG. 3 in the direction of the arrows at a scale which is enlarged as compared to FIG. 3;

FIG. 5 is a partly sectional fragmentary top plan view of the intermediate portion of the assembled bar means illustrating the attaching means and part of the tether means attached thereto; and

FIG. 6 is a sectional elevation of the ball of the tether-ball assembly showing not only the details of the ball but also how the ball is attached to the tether means.

10 DESCRIPTION OF A PREFERRED EMBODIMENT

Referring to FIG. 1, the tether-ball assembly 10 of the invention which is illustrated therein includes an elongated bar means 12, a support means 14 supporting the bar means 12 in a substantially horizontal attitude at a given distance above a given supporting surface, this supporting surface 16 being in the illustrated example a floor of a room or any suitable ground surface on the outside. An attaching means 18 is fixed to the bar means 12 intermediate its ends for attaching to the bar means 12 an elongated flexible tether means 20 a ball 22 is attached to the tether means 20 at its end distant from the bar means 12.

The several components referred to above are shown 25 disassembled from each other in the exploded perspective view of FIG. 2. Thus it is clear from FIG. 2 that the bar means 12 is composed of a pair of elongated hollow tubular bar sections 24a and 24b which may be inexpensively manufactured from any suitable well known plastic material, for example.

The support means 14 is composed of a pair of supporting components 26a and 26b which are connected to the opposed ends of the bar means 12 by a pair of connecting means 28a and 28b.

30 The pair of supporting components 26a and 26b are of substantially triangular configuration and are integrally formed with the pair of connecting means 28a and 28b. Each supporting component and connecting means may be integrally molded so as to form a one-piece body of plastic.

Referring in particular to FIGS. 3 and 4, it will be seen that each of the components 26a and 26b includes a substantially vertical wall 30 connected along its entire periphery to an inwardly directed flange 32. Along its lower portion this flange as well as the wall 30 are curved upwardly away from the supporting surface 16. Through this expedient the weight of the bar means 12 is more precisely distributed to the opposed ends of the lower portions of the pair of supporting components 26a and 26b.

45 The integral connecting means 28a is in the form of an elongated hollow tube extending through and beyond the space defined by the wall 30 in the flange 32. This tube 34 of the connecting means 28a is integrally formed at its exterior with longitudinally extending ribs 36. These ribs 36 are particularly apparent from FIG. 4 which also shows the enlarged thickened plastic portion 38 where the connecting means 28a is joined to the wall 30. The connecting means 28b is joined in the same way to the wall 30 of the component 26b.

50 Thus, the interior diameters of the pair of bar sections 24a and 24b is such that they can be slipped onto the pair of connecting means 28a and 28b frictionally engaging the ribs 36 so that they have a fairly snug fit on the pair of connecting means. By the use of these ribs the area of frictional contact between the bar sections and the connecting means is reduced so that the

parts can be more easily assembled and disassembled.

As is shown most clearly in FIG. 2, the attaching means 18 includes an elongated plastic tubular component 40 having a flanged element 42 projecting from its exterior surface. Actually this element is integral with an interior transverse partition of the elongated element 40. The elongated portions of element 40 which project in opposite directions beyond the flanged element 42 taper so that they can be easily received in the open ends of the bar sections 24a and 24b which are directed toward each other. With the free ends of elongated element 40 received in the adjoining ends of elements 24a and 24b, these elements are pushed together so that they directly engage the flange element 42, and of course the supporting components 26a and 26b are also pushed toward each other so that the ends of the bar sections 24a and 24b distant from the attaching means 18 directly engage the thickened portion 38 at the inner end of each connecting means 28a and 28b. Thus, with the parts assembled in this way they will remain in their assembled condition resting very stably on a supporting surface such as the surface 16. This surface 16 may be floor or outside ground, as pointed out above. However, it may also be the surface of a table, if desired. The pair of components 26a and 26b need not be attached in any way to the surface 16 since they will remain stably at a desired location simply by resting on the surface 16, and of course none of the components require any tools or fasteners in their connection and disconnection so that all of the parts are very easy to assemble and disassemble and occupy an extremely small space when in the disassembled condition.

The flanged element 42 of the attaching means 18 projects upwardly beyond the bar means 12, and at this upward projecting portion is formed with an opening 44 for receiving a hook 46 at one end of a relatively short ball chain component terminating at its opposite end in a hook to which one end of an elongated flexible elastic narrow strip or tape 48 is attached. Thus, these components namely element 48 and the small flexible hooked element for connecting element 48 to the flange 42 form the tether means 20.

The end of element 48 distant from the flange 42 is connected by a suitable knot, to a strap 50 which is fixed in any suitable way, as by gluing, a suitable solvent, or the like, to the exterior surface of the ball 52. This ball 52 is made of a suitable plastic, for example, and is capable of being inflated through a suitable opening by the operator, the opening through which the ball is inflated being held closed by a suitable plug 54, as shown schematically in FIG. 6. Thus, the light-weight inflated ball 52 is readily attached by way of its strap 50 to the tether means 20 which in turn is readily attached by way of the hook 46 to the attaching means 18.

The ball 52 while appearing to be of a rather large size nevertheless has an extremely light weight and in connection with the elasticity of the tether element 48 provides an erratic movement each time the ball is propelled toward one side or the other side of the bar means 12. This propelling of the ball may take place by way of suitable bats or tennis rackets, such as the element 58 shown in FIG. 1. With the structure as shown in FIG. 1, it is possible for a single player to use the structure simply by propelling element 22 up against a wall on the other side of the bar means 12 from the bat

58, and the ball 22 will rebound back to the player who can repeatedly propel the ball in this way toward the wall.

However, it is also possible for another player to be situated on the opposite side of the bar means 12 so that in the manner of a tennis game it is possible for opposed players to propel the tether ball back and forth over the bar means 12.

In addition, it is possible to play doubles, by having 10 a pair of players situated on each side of the bar means 12. Because of the stretchability of the component 48 of the tether means 20 when doubles type of playing takes place the ball 22 will be reliably propelled to a considerable distance from one to the other of the players with the trajectory of the ball being affected in an unexpected manner due to the elasticity of element 48, so that in this way a considerable added interest is achieved, contributing greatly to the enjoyment of the game.

20 When it is desired to store the game, it is a simple matter to slip the pair of sections 24a and 24b from the attaching means 18 and the pair of supporting components 26a and 26b, and then all of the parts can be stored in an extremely small space until they are again 25 to be used.

Inasmuch as most of the above components can be 30 made of plastic, the components are extremely inexpensive to manufacture, and the game of the invention is thus capable of being widely used by a large number of people.

What is claimed is:

1. In a tether-ball assembly, elongated bar means, support means operatively connected with said bar means for supporting the latter in a generally horizontal attitude at an elevation above a given supporting surface, elongated flexible tether means, including an elongated elastic filamentary element so that said tether means is stretchable, said tether means being substantially longer than said elevation, attaching means carried by said bar means intermediate the ends thereof for attaching said tether means thereto, and a ball attached to said tether means at an end thereof distant from said bar means to rest on said surface when not in use so that a player on one side of said bar means can propel the ball over said bar means toward the other side of said bar means to be returned to the player on said one side of said bar means, said ball carrying a means for releasably attaching said tether means thereto, and said ball being a light-weight inflatable ball and having an opening through which the ball may be inflated by the operator, said ball carrying a plug for closing said latter opening.

2. In a tether-ball assembly, elongated bar means, support means operatively connected with said bar means for supporting the latter in a generally horizontal attitude at an elevation above a given supporting surface, elongated flexible tether means, including an elongated elastic filamentary element so that said tether means is stretchable, said tether means being substantially longer than said elevation, attaching means carried by said bar means intermediate the ends thereof for attaching said tether means thereto, and a ball attached to said tether means at an end thereof distant from said bar means to rest on said surface when not in use, so that a player on one side of said bar means can propel the ball over said bar means toward the other side of said bar means to be returned to the

player on said one side of said bar means, said attaching means including a flanged element formed with an opening, said tether means having adjacent said bar means a hook to be received in said opening of said flange element.

3. In a tether-ball assembly, elongated bar means, support means operatively connected with said bar means for supporting the latter in a generally horizontal attitude at an elevation above a given supporting surface, elongated flexible tether means, including an elongated elastic filamentary element so that said tether means is stretchable, said tether means being substantially longer than said elevation, attaching means carried by said bar means intermediate the ends thereof for attaching said tether means thereto, and a ball attached to said tether means at an end thereof distant from said bar means to rest on said surface when not in use, so that a player on one side of said bar means can propel the ball over said bar means toward the other side of said bar means to be returned to the player on said one side of said bar means, said support means supporting said bar means at said elevation exclusively by resting on said supporting surface without being attached thereto.

4. The combination of claim 3 and wherein said support means includes a pair of end support members carrying, respectively, a pair of connecting means for releasably connecting said end support members to opposed ends of said bar means.

5. The combination of claim 4 and wherein said bar means has a pair of opposed elongated hollow tubular portions at its ends, and said releasable connecting means carried by said end support members including a pair of elongated inserts to be received in said tubular ends of said bar means.

6. The combination of claim 5 and wherein said end inserts have exterior longitudinally extending ribs for reducing the area of frictional engagement between said bar means and said releasable connecting means carried by said end support members.

7. In a tether-ball assembly, elongated bar means, support means operatively connected with said bar means for supporting the latter in a generally horizontal attitude at an elevation above a given supporting surface, elongated flexible tether means, attaching means carried by said bar means intermediate the ends thereof for attaching said tether means thereto, and a ball attached to said tether means at an end thereof distant from said bar means, so that a player on one side of said bar means can propel the ball toward the other side of said bar means to be returned to the player on said one side of said bar means, said support means supporting said bar means at said elevation exclusively by resting

on said supporting surface without being attached thereto, said support means including a pair of end support members carrying, respectively, a pair of connecting means for releasably connecting said end support

5 members to opposite ends of said bar means, said bar means having a pair of opposed elongated hollow tubular portions at its ends, and said releasable connecting means carried by said end support members including a pair of elongated inserts to be received in said tubular 10 ends of said bar means, said end inserts having exterior longitudinally extending ribs for reducing the area of frictional engagement between said bar means and said releasable connecting means carried by said end support members, said bar means being in the form of an 15 elongated tubular bar split intermediate its ends to form a pair of bar sections, and said attaching means including an elongated member having intermediate its ends a flanged attaching element projecting from said elongated member, said elongated member being insertable on both sides of said attaching means into said bar sections.

20 8. The combination of claim 7 and wherein said portions of said elongated member on opposed sides of said attaching means are tapered to facilitate entry into said bar sections.

25 9. In a tether-ball assembly, elongated bar means, support means operatively connected with said bar means for supporting the latter in a generally horizontal attitude at an elevation above a given supporting surface, elongated flexible tether means, including an elongated elastic filamentary element so that said tether means is stretchable, said tether means being substantially longer than said elevation, attaching 30 means carried by said bar means intermediate the ends thereof for attaching said tether means thereto, and a ball attached to said tether means at an end thereof distant from said bar means to rest on said surface when not in use, so that a player on one side of said bar means can propel the ball over said bar means toward the other side of said bar means to be returned to the player on said one side of said bar means, said support means, bar means, and attaching means all being made of components carrying means for releasably assembling and disassembling said components without the use of fasteners while retaining said components frictionally in an assembled condition with said support means itself resting on said supporting surface without being attached thereto so that the entire assembly can be set up and broken down without requiring the use of tools or without requiring manipulations for fastening elements.
